UNITED STATES PATENT OFFICE.

PAUL PUESCHEL, OF MILWAUKEE, WISCONSIN.

WAGON-BRAKE.

SPECIFICATION forming part of Letters Patent No. 398,799, dated February 26, 1889.

Application filed November 22, 1888. Serial No. 291,528. (No model.)

To all whom it may concern:

Be it known that I, PAUL PUESCHEL, of Milwaukee, in the county of Milwaukee, and in the State of Wisconsin, have invented certain new and useful Improvements in Carriage and Wagon Brakes; and I do hereby declare that the following is a full, clear, and exact description thereof.

My invention relates to carriage and wagon brakes; and it consists in certain peculiarities of construction and combination of parts, to be hereinafter described with reference to the accompanying drawings and subsequently claimed.

In the drawings, Figure 1 represents a perspective view of the brake in connection with the running-gear of a two-horse carriage; Fig. 2, a similar view of the brake in connection with the running-gear of a one-horse carriage; Fig. 3, a detail sectional view illustrating the manner of connecting the brake with a carriage pole or tongue; Fig. 4, a perspective view showing the application of the brake to a non-elliptic-spring carriage; Fig. 5, a detail side elevation of the thill-connections employed in that form of my invention shown in the preceding figure, and Fig. 6 a sectional view showing the brake applied to the front truck of a wagon.

Referring by letter to the drawings, A represents a transverse rod or brake-beam having crank-bends b and forwardly-extended arms c, the latter terminating in crank-bends d, on which are secured brake-shoes B.

In Figs. 1, 2, and 6 the rod A is shown as having its crank-bends b supported in guide-loops C, clipped to elliptic springs D, that are in turn clipped to the front axle, E, of the vehicle to which my invention may be applied, while in that style of vehicle shown in Fig. 4 the guide-loops form horizontal forward extensions at the upper ends of vertical rods F, the lower ends of these rods being also provided with horizontal forward extensions c', from which rise goose-necks d', that terminate in spring-shackles e, the latter in the construction shown by Fig. 4 being connected to the lower horizontal extensions of said vertical rods by means of straps G, passed through

eyes f/g, respectively arranged on said shackles and rod-extensions, as best illustrated by Fig. 5.

In that style of vehicle illustrated by Fig. 1 the hounds H are connected to the springs D and front and rear cross-braces, I J, the front brace being provided with a depending loop, h, through which is passed a tongue, K, the butt of the latter being inserted in a socket, L, attached to the rear cross-brace. Secured to the under side of the tongue, by means of bolts i/j, is a plate, M, and secured to a stud, k, on this plate is a longitudinal rod, N, having a screw-threaded rear end, m, by which it is adjustably connected to a shackle, O, on the brake-beam A, as best illustrated in Fig. 3. Depending from the loop h is an eye, n, to which is secured one end of a spiral spring, P, the other end of this spring being connected to another eye, o, that depends from the plate M upon the under side of the tongue. The spring P is arranged to exert its force in an outward direction, and consequently the normal position of the tongue is such that the brake-beam connected thereto by the longitudinal rod N is drawn forward in the guide-loops C to hold the shoes B away from the front wheels, Q, and prevent rattling when the vehicle is running on a level; but when the horses are held back the force of said spring is overcome and the rearward movement of the tongue and brake-beam brings the shoes against said wheels. The brake-beam A being hung above the centers of the wheels Q, the shoes B will not bind against these wheels when the vehicle is being backed by the team; but when said team is being held back while the vehicle is moving forward the movement of said wheels against the shoes tend to draw against the resistance of beam A and cause a tight lock of the brake.

In that style of vehicle shown in Figs. 2 and 4 there are two of the rods N, adjustably connected at their rear ends to shackles O on the brake-beam and at their forward ends to the thill-bolts p, the spring-shackles e acting in place of the spiral spring P, employed on that style of vehicle previously described.

In that style of vehicle shown by Fig. 2 the draft comes upon the hounds H; but in the construction shown by Fig. 4 the draft is upon the axle E, and the strain upon the spring-shackles is resisted by the straps G.

In the construction shown by Fig. 6 the

tongue-socket L is omitted, and the butt of the tongue plays back and forth in bands r, that embrace the hounds H, this play being limited by the bolt i, by which the plate M is secured 5 to said tongue.

To detach the tongue shown in Figs. 1 and 3, the bolts i j are removed, while the tongue shown in Fig. 6 can be detached upon the removal of the single bolt that connects it with 10 the plate to which the brake-rod N is secured.

Having thus fully described my invention, what I claim as new, and desire to secure by Letters Patent, is—

1. A carriage or wagon brake that comprises a horizontal beam shaped at both ends to form forwardly-extended cranks, shoes carried by the cranks, stationary guide-loops arranged to loosely support the beam, and a longitudinal rod or rods uniting said beam 20 with the draft-gear of the vehicle to which the brake may be connected, substantially as set forth.

2. A carriage or wagon brake that comprises a horizontal beam terminated at both 25 ends in forwardly-extended cranks, shoes carried by the cranks, stationary guide-loops arranged to support the beam, and a rod or rods adjustably connected to said beam and united to the draft-gear of the vehicle to which the 30 brake may be connected, substantially as set forth.

3. A carriage or wagon brake that comprises a horizontal beam shaped at both ends to form forwardly-extended cranks, shoes carried by the cranks, stationary guide-loops arranged to loosely support the beam, a plate 35 secured to the vehicle-tongue, and a longitudinal rod connecting the plate with said beam, substantially as set forth.

4. A carriage or wagon brake that comprises a horizontal beam terminated at both 40 ends in forwardly-extended cranks, shoes carried by the cranks, stationary guide-loops arranged to support the beam, a rod or rods for uniting said beam with the draft-gear of the vehicle, to which the brake may be connected, and a spring or springs arranged to normally hold 45 said draft-gear in such position that the shoes are away from the adjacent wheels, substantially as set forth.

5. A carriage or wagon brake that comprises a horizontal beam shaped at both ends to form forwardly-extended cranks, shoes car-

ried by the cranks, stationary guide-loops arranged to loosely support the beam, a plate 55 secured to the vehicle-tongue, a supporting-loop for the tongue, a spiral spring connecting the plate and supporting-loop, and a longitudinal rod uniting said plate and beam, substantially as set forth.

6. A carriage or wagon brake that comprises a horizontal beam terminated at both ends in forwardly-extended cranks, shoes carried by the cranks, stationary guide-loops arranged to support the beam, and a rod uniting 60 said beam with the tongue of the vehicle, to which the brake may be applied, in combination with a socket arranged to receive the butt of said tongue, substantially as set forth.

7. In a vehicle, the combination of vertical 70 rods having their upper ends terminated in horizontal forwardly-extended guide-loops and their lower ends provided with horizontal forward extensions clipped to an axle of the vehicle, goose-necks forming continuations of said extensions and terminated in spring-shackles, a horizontal beam loosely supported in the guide-loops and shaped at both ends to form forwardly-extended cranks, shoes carried by the cranks, thills secured to the 80 spring-shackles, and rods connecting said shackles and beam, substantially as set forth.

8. In a vehicle, the combination of vertical rods having their upper ends terminated in horizontal forwardly-extended guide-loops 85 and their lower ends provided with horizontal forward extensions clipped to an axle of the vehicle, goose-necks forming continuations of said extensions and terminated at both ends in forwardly-extended cranks, straps connecting the shackles and lower horizontal extensions of the vertical rods, a horizontal beam loosely supported in the guide-loops and shaped at both ends to form forwardly-extended cranks, shoes carried by the cranks, 90 thills connected to said spring-shackles, and rods uniting these shackles and the beam, substantially as set forth.

In testimony that I claim the foregoing I have hereunto set my hand, at Milwaukee, in 100 the county of Milwaukee and State of Wisconsin, in the presence of two witnesses.

PAUL PUESCHEL.
